COACH FOR PICK-UP TRUCKS

Antonio J. Hamel, Everett N. Hamel, and Donald A. Hamel, Lakeview, Calif.

Application May 12, 1958, Serial No. 50,849

Term of patent 14 years

(Cl. D14—3)

FIG. 1.

FIG. 2.

FIG. 3.

FIG. 4.

The essential features of our design reside in the portions shown in full lines.

We claim:

The ornamental design for a coach for pick-up trucks, substantially as shown and described.
